O. DOBBELSTEIN ET AL.
ANNULAR KILN FOR DRYING AS WELL AS FOR CARBONIZING
SOLID CARBONACEOUS OR THE LIKE MATERIALS
Filed Jan. 24, 1925

OTTO DOBBELSTEIN, OF ESSEN, AND HERMANN HESS, OF DUISBURG, GERMANY.

ANNULAR KILN FOR DRYING AS WELL AS FOR CARBONIZING SOLID CARBONACEOUS
OR THE LIKE MATERIALS.

Application filed January 24, 1925. Serial No. 4,512.

To all whom it may concern:

Be it known that we, OTTO DOBBELSTEIN and HERMANN HESS, German citizens, and residing at Essen and Duisburg, respectively, both in Germany, have invented certain new and useful Improvements in an Annular Kiln for Drying as Well as for Carbonizing Solid Carbonaceous or the like Materials (for which we have filed an application for patent in Germany on 2nd February, 1924, No. D. 44,871 VI/10°), of which the following is a specification.

This invention relates to an improved annular kiln with bottom heating and gas collector, for drying as well as for carbonizing solid carbonaceous or the like materials of any kind such as coal, ores, bituminous slate, and the like.

The accompanying drawing represents the improved annular kiln: Figs. 1 and 2 are perpendicular sections, respectively on the lines 1—1 and 2—2 of Fig. 3 which shows the kiln in a plan view.

The annular kiln comprises a series of concentric ring pockets *a* and of ring spaces *b* with open lower ends between the single ring pockets, for heating the latter. Said ring pocket system rotates above an annular heating channel *c*. Above the rotary ring pocket system a stationary annular collector *d* is located for collecting the vapors produced, for instance when carbonizing coal, and leading the same off through vapor offtake pipes *d'*.

For separately gaining the differently composed gases escaping from the single zones during the carbonizing process, radial partition-walls (such as indicated at *e*, Fig. 3) extending down to the top of the rotary ring pocket system, may be provided in said collector *d*.

Heating may be effected by means of waste-gases or by gas-burners. The bottom of the heating channel *c* ascends from the outer circumference toward the middle of the annular kiln up to the bottom of the ring pocket system (Fig. 1), so that the heating gases are compelled to travel through the spaces *b* between the single ring pockets *a*. Between the admission *c'* and the outlet *c''* of the heating gases a partition-wall *f* (Fig. 3) is provided in the heating channel *c*, which wall is comb-shaped in such

a way that its teeth at this place fill out the spaces *b* between the single ring pockets *a*. 55

For carbonizing coal, the latter is automatically supplied into the ring pockets *a* through a hopper *x* extending from above through the bonnet *d* down to the top of the ring pocket system and is then slowly rotated with the latter in the direction of arrow *z* (Fig. 3). The heating gases travel in opposite direction. The admission of the heating gases into the heating channel *c* takes place underneath the place, where the materials after their finished treatment are excavated, so that there the meanwhile produced coke receives its strongest heating and thereby a great firmness. The excavation of the coke takes place automatically by the latter, owing to the rotation of the ring pocket system, travelling up, in the direction of arrow *o*, the upwardly inclined plane of a comb-shaped stationary excavator *g* (Fig. 2) extending into each ring pocket down to 75 the bottom of the same. The ring of the gas collector *d* is interrupted above said excavator *g* so that the coke after its ascent from the ring pockets *a* can be excavated in lateral direction by means of a conveyor *h* (Fig. 80 2) radially arranged above the ring pocket system.

The excavation of the materials from the ring pockets *a* can also be effected by means of an elevator, bucket-wheel, or the like. 85

To attain a greater firmness of the coke to be produced, the coal supplied from the hopper *x* can be compressed by means of a stamper, pressure-rolls, or the like.

If, for certain reasons, it is desired to 90 make the ring pocket system stationary, consequently, the gas collector *d* with hopper *x* and excavator *g*, must be rotary above the ring pocket system; this being obviously clear without further illustration. 95

In some cases, particularly for drying non-baking materials, it may be desirable to so construct the annular kiln that the excavation does not take place to up above but to down below. In this case, the ring pockets *a* for the reception of the goods must be open at the lower ends; their closure is then effected by means of a stationary bottom plate provided with annular slots 100 for a passage therethrough of the heating gases to the spaces *b* and completely inter- 105

rupted below the excavator, so that the upwardly directed comb teeth of the latter can force out the materials in downward direction where the same are led off by a conveyor.

The improved annular kiln ensures by its large heating surface a high capacity. The materials to be dried or to be carbonized are kept at perfect rest during their slow rotation, so that a formation of dust is perfectly prevented. The single parts of the annular kiln are accessible from all sides.

What we claim, is:—

1. An annular kiln for drying as well as for carbonizing solid carbonaceous or the like materials, comprising, in combination: a rotary series of concentric ring pockets having ring spaces with open lower ends between the single ring pockets, a stationary annular heating channel below said ring pocket system, a stationary annular gas collector above said ring pocket system having vapor offtake pipes, a stationary feeding hopper extending from above through said collector down to the top of the ring pocket system, and stationary means for excavating the materials from said pockets after their finished treatment; said heating channel having an admission opening located underneath the excavation place of the materials

and an outlet opening located underneath said feeding hopper.

2. An annular kiln as specified in claim 1: in which the bottom of said annular heating channel ascends from the outer circumference toward the middle of the annular kiln.

3. In an annular kiln as specified in claim 1: a comb-shaped partition-wall between the admission and the outlet opening of said annular heating channel, the comb teeth of said wall extending into and filling out the spaces between the single ring pockets at this place.

4. In an annular kiln as specified in claim 1: radial partition-walls in said gas collector extending down to the top of the rotary ring pocket system.

5. An annular kiln as specified in claim 1: in which said excavating means consists of a comb-shaped inclined plane extending from the bottom of each single ring pocket up to the top of the same, and of a conveyor located above said excavator; the ring of the gas collector being interrupted between said excavator and conveyor.

In testimony whereof we have hereunto set our hands.

OTTO DOBBELSTEIN.
HERMANN HESS.
